[57] CLAIM

The ornamental design for a side folding pocket knife, substantially as shown.

DESCRIPTION

FIG. 1 is a side view of the side folding pocket knife, with the blade shown in its open position, with the opposite side being substantially identical thereto;

FIG. 2 is a top view thereof;

FIG. 3 is a bottom view thereof;

FIG. 4 is an end view thereof, showing the butt end of the handle;

FIG. 5 is an end view thereof, showing the pointed portion of the blade;

FIG. 6 is a side view of the side folding pocket knife, showing the blade folded into the handle, with the opposite side being substantially identical thereto;

FIG. 7 is an end view thereof, showing the ends of the arms of the handle and the butt of the blade tang.
